CLAIM

The ornamental design for a fluid transfer device, as shown and described.

DESCRIPTION

FIG. 1 is a front perspective view of an example of a fluid transfer device with various features shown in broken lines; FIG. 2 is a rear perspective view of the device of FIG. 1; FIG. 3 is a front view of the device of FIG. 1; FIG. 4 is a back view of the device of FIG. 1; FIG. 5 is a right side view of the device of FIG. 1; FIG. 6 is a left side view of the device of FIG. 1; FIG. 7 is a top view of the device of FIG. 1; and, FIG. 8 is a bottom view of the device of FIG. 1. The broken lines shown in FIGS. 1-8 illustrate portions of the fluid transfer device that form no part of the claimed design.
